UNITED STATES PATENT OFFICE.

JOSEPH SCHNEIBLE, OF NEW YORK, N. Y.

REGULATING-VALVE.

SPECIFICATION forming part of Letters Patent No. 636,856, dated November 14, 1899.

Application filed July 24, 1899. Serial No. 724,891. (No model.)

To all whom it may concern:

Be it known that I, JOSEPH SCHNEIBLE, a citizen of the United States, residing in the borough of Manhattan, city of New York, State of New York, have invented certain new and useful Improvements in Regulating-Valves, of which the following is a specification, reference being had to the accompanying drawing, forming a part hereof.

This invention relates to regulating-valves in which the position of the valve-plug is determined by a diaphragm or piston subject to the pressure of the fluid which flows through the valve and in which the action of such diaphragm or piston is regulated or controlled by the pressure of a spring, means being provided to adjust such pressure. Usually the spring bears directly upon the diaphragm or piston or upon the valve - stem connected therewith, and the expansion or contraction of the spring is equal to the extent of movement of the diaphragm and of the valve-plug. Under some conditions of use it is desirable that the valve-plug shall have a relatively large movement for a given amount of expansion or contraction of the spring, and again it is oftentimes desirable that the spring should have a relatively large expansion or contraction for a given movement of the valve-plug, as this relation makes it possible to employ a spring of less stiffness and to secure great delicacy and sensitiveness in the operation of the valve. It is the object of this invention to provide for securing such desirable variation or relative difference of movement between the spring and the diaphragm or piston or valve-stem; and the invention consists in means whereby this result is accomplished.

The accompanying drawing represents in vertical central section one form of regulating-valve which embodies the invention.

In the construction represented in the drawing the usual valve-body A is provided with a double valve-seat a a' and supports upon an enlargement A' the usual diaphragm B, the latter being held to its seat by a shell or casing C. The valve stem and plug D is secured to the diaphragm in the usual manner and at its lower end is reduced to form a shoulder d and spindle d'. A ring d², of suitable material to coöperate with the valve-seat, is slipped upon the spindle d' to abut against

the shoulder d and is followed by a sleeve d³. A second ring d⁴, of like material, is slipped upon the spindle to abut against the sleeve d³, and all of the parts are held firmly together by a nut d⁵. This construction facilitates manufacture and permits the operative portions of the valve-plug to be replaced readily when necessary without removing the valve plug and stem. A passage a² from the valve-chamber to the diaphragm-chamber permits the pressure of the fluid to be transmitted to the diaphragm.

The spring E, which exerts its pressure upon the diaphragm in opposition to the pressure of the fluid, is supported in line with the axis of the valve-stem and diaphragm in a suitable spring-box e, which forms a part of the casing C, and is adjusted by a screw e', as usual. Its lower end may be provided with a cap or shoe e². Instead of acting directly upon the diaphragm or valve - stem the spring acts through one or more levers F. Two levers are preferably employed and may be held from displacement by a yoke e³, secured to the shoe e², and a pin e⁴, which passes through the ends of the levers. Bearing-points for the levers are provided in the shell or casing C, as at c, and in the construction shown, in which the range of movement of the free end of the spring is to be greater than the range of movement of the diaphragm, intermediate bearing-points are provided for the levers against the diaphragm. For convenience a cap B' is applied to the diaphragm, being held in position by the head of a nut b on the end of the valve-stem, on which it rests centrally, and is formed to provide the intermediate bearing-points for the levers F, as at b'. The cap is free from the plate of the diaphragm and secures the proper balance of the levers. It will now be seen that the relative movement of the spring and the diaphragm or valve-stem will be dependent upon the relative arrangement of the bearing-points for the levers and that in the construction shown the spring will have a larger movement and that consequently a spring of less relative stiffness may be employed and the valve will be correspondingly delicate and sensitive in operation.

It will be understood that the invention is not to be limited to the precise construction

and arrangement of parts shown and described herein.

I claim as my invention—

The combination with a valve-body having 5 a valve-seat, a valve-stem, a diaphragm, a casing closing said diaphragm in and a spring coöperating with the diaphragm, and included within the casing in line with the axis of the 10 diaphragm, of a shell or casing covering the diaphragm, a cap resting upon the diaphragm and provided with bearing-points and levers

having bearing-points at their outer ends against said shell or casing and at intermediate points against the cap, and receiving at their inner ends the pressure of the spring, 15 substantially as shown and described.

This specification signed and witnessed this 17th day of July, A. D. 1899.

JOSEPH SCHNEIBLE.
